CHARLES F. MILLER, OF MOORES, PENNSYLVANIA, ASSIGNOR TO WESTINGHOUSE ELECTRIC & MANUFACTURING COMPANY, A CORPORATION OF PENNSYLVANIA

STOKER

Application filed November 6, 1929. Serial No. 405,167.

My invention relates to combustion apparatus, and more particularly to progressive feed stokers, and it has for an object to increase the efficiency of apparatus of this 5 character.

As is well known, the side retort stoker consists of a retort disposed along one wall of the furnace, and an air-emitting grate extending laterally from the upper edge 10 of the outer wall of the retort. The grate may be either movable or stationary. Fuel is fed longitudinally of the retort and at the same time upwardly and laterally over the side thereof. The fuel overflowing from 15 the retort moves onto the laterally-extending grate where it is burned.

If the grate be a movable one, such movement will aid, to some extent, in the feeding of the fuel thereon from the retort. However, in all cases heretofore known to me, 20 the main force effecting the feeding of the fuel is that of gravity. Consequently, in order that the grate surface may have at all times, the proper amount of fuel, it is necessary to operate with an extremely thick fuel 25 bed over and adjacent to the retort.

An excessively thick fuel bed over the retort will also result in a thick fuel bed at the upper end of the grate surface which is adjacent the retort. The air cannot effectively penetrate the thick fuel bed and therefore the proper combustion condition cannot be maintained at that point. Also, the mass of fuel over and adjacent the retort 30 will matt or fuse together and be very difficult to move. Furthermore, as the lower portion of the overfeed grate is the only point where air can pass freely, air will pass through that portion in excess amounts 35 and as this excess air has to be heated to stack temperature, the efficiency of the stoker will be lowered to a still greater degree.

More particularly, therefore, it is an object of this invention to provide an improved 40 form of stoker having an effective means for positively feeding the coal overflowing from the retort onto a laterally-extending grate surface, thereby making possible a thinner fuel bed and more efficient combustion.

50 These and other objects are effected by my

invention, as will be apparent from the following description and claims taken in connection with the accompanying drawings, forming a part of this application, in which:

Fig. 1 is a transverse sectional view 55 through a stoker constructed in accordance with my invention and taken on the line I—I of Fig. 2;

Fig. 2 is a longitudinal sectional view 60 through the stoker taken on the section lines II—II of Fig. 1;

Fig. 3 is an enlarged fragmentary sectional view taken on the line III—III of Fig. 2; and,

Fig. 4 is an enlarged fragmentary detail 65 illustrating the adjustment of the driving mechanism and taken on the line IV—IV of Fig. 1.

According to the embodiment of my invention shown on the accompanying drawings, I provide a stoker comprising a retort disposed adjacent one wall of the furnace, an air-emitting grate surface extending laterally from the upper edge of the retort side wall which is remote from the furnace wall, and means for feeding fuel longitudinally of the retort and upwardly and laterally over the side thereof. I also provide a fuel-pushing means which is disposed above the retort side wall adjacent the furnace wall and operates to feed the fuel overflowing from the retort onto the lateral grate section; thereby making possible the carrying of a much thinner fuel bed over the retort and over the upper end of the laterally-extending grate 75 than has heretofore been possible.

Referring now in detail to the construction illustrated, it will be observed that I have shown on the accompanying drawings a furnace 10 comprising front and rear walls 11 and 12, respectively, and side walls 13 and 14, respectively. A single retort underfeed stoker 15 is disposed within the furnace and divides the same into an air chamber 16 and a combustion chamber 17. Air is supplied to 90 the air chamber by means of an air duct 18.

The stoker comprises a retort 19, a laterally-extending and movable grate 20, and a dump grate 21. The retort comprises a bottom wall 22, and side walls 23 and 24, re- 100

spectively. The side wall 23 is shown as being divided longitudinally into a lower section 25 and an upper section 26 detachably secured by bolts 27 to the section 25. The overfeed grate is so designed as to permit the free passage of air therethrough and comprises parallel grate bars 28, 28, slidably supported at their upper ends by the retort side wall 24 and at their lower ends by an I-beam 29. The dump grate 21 is supported at its forward end by a shaft 30 and may be operated by suitable mechanism (not shown) connected to the shaft.

Fuel is fed from a suitable hopper 31 and into the ends of the retort by a primary ram 32. A secondary ram 33 is slidably supported by the bottom wall of the retort and is operatively connected to the primary ram by a connecting rod 34. As is well known, the action of the secondary ram is such that the fuel is fed longitudinally of the retort and at the same time upwardly and laterally over the side wall 24 and onto the overfeed grate 20.

As stated, I provide an improved means for aiding in the feeding of the coal onto the overfeed grate section. As shown, I provide a movable wall 35 which forms an upward extension of the side wall 23 of the retort and is pivotally supported by the upper section 26 of such side wall. The pivotal connection between the wall 35 and the section 26 is provided by a cylindrical enlargement 36 formed integral with the upper surface 36 of the section 26, and fitting within sockets 37 provided by an arcuate portion 38 of the movable wall 35, and cooperating arcuate portions 39 formed on brackets 40, which latter are detachably secured by bolts 41 to the rear portion of the wall 35.

The wall 35 may be in one piece which extends for the whole length of the retort. Preferably, however, it is divided transversely into a plurality of sections 42 to facilitate repair. It will be observed that a space is provided between the ends of the wall 35 and the furnace walls 11 and 12, respectively. The reason for this is to permit the wall 35 to expand due to heat. The spaces between the ends of the wall 35 and the furnace walls 11 and 12 are sealed by plates 43 disposed behind the ends of the wall 35 and held against the furnace walls by counterweighted follower mechanisms 44. (See Figs. 2 and 3.) A follower 45 engages the end of each sealing plate 43. The follower is keyed to a shaft 46 carried by the wall 35 and a guide plate 47, which latter is also secured to the wall 35. A counterweighted lever arm 48 is also keyed to the shaft and serves to urge the follower against the sealing plate.

The wall 35 fits within a recess 49 formed within the furnace wall 13. The lower portion of the recess is in open communication

with the air chamber or wind box 16, and the upper portion of the recess communicates with the combustion chamber through openings 50 formed in plates 51. The plates 51 rest loosely on the flanged upper portion 70 of the wall 35 and are held in position by spaced flanges 52 projecting downwardly from a supporting plate 53 for the furnace wall 13.

It will thus be seen that I have provided means for supplying air for combustion over the retort. If desired, the number of openings 50 may be increased or reduced, or the opening may be done away with, depending, of course, upon the combustion condition required and the character of the coal used.

Means is provided for reciprocating the laterally-extending grate 20 and for oscillating the wall 35 about its pivotal support, so that the fuel overflowing from the retort 19 will be positively and effectively fed on the grate 20. As shown, an oscillating power shaft 54 is disposed transversely beneath the grate 20 and is provided with one or more upwardly-extending operating arms 55 which are connected to the grate 20 by means of a cylinder and socket connection 56. The shaft 54 is adapted to be oscillated by any suitable means disposed exteriorly of the stoker (not shown).

The shaft 54 is also provided with one or more downwardly-extending lever arms 57, each of which is pivotally connected at its lower end by a lost motion connection 58 to an end of a link 59. The opposite end of each link 59 is pivotally connected to the lower end of an arm 60. The arms 60 are each rigidly secured at their upper ends to one of the brackets 40.

The lost motion connections 58 may be adjusted to vary the degree of motion imparted to the wall 35 from the shaft 54. Referring to Figs. 1 and 4, it will be observed that the lower portion of each of the arms 57 is bifurcated to receive the end of the link 59. The end of the link 59 is provided with a longitudinally-extending slot 61 and a plurality of spaced openings 62. The bifurcated end of the lever arm is secured to the end of the link by a pin 63 extending through aligned openings in the arm and the slot 61 in the link. A block 64 fits over the link 59 and may be secured thereto by a pin 65 fitting within aligned openings in the block and any one of the openings in the link. It will thus be seen that the motion of the lever arm toward the left of the drawings is transmitted through the block 64 to the link 61. As the position of the block 64 may be varied with respect to the arm 57, more or less lost motion may be had, thereby varying the degree of motion imparted to the movable wall 35.

The operation of the stoker will be apparent from the above description. The coal is

fed longitudinally of the retort and at the same time upwardly toward the top thereof, by the rams. The fuel overflowing from the retort is positively pushed onto the grate by the movable wall. By reason of this construction, a relatively thin fuel bed can be carried over the retort and the upper end of the grate, thereby permitting the air to pass freely through the upper portion of the fuel bed and combine efficiently with the volatiles and solid carbons to produce combustion. While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In stoker apparatus, the combination with a fuel trough having bottom and side walls; of a plate-like member disposed above one of the side walls, means for supporting the plate-like member adjacent its lower edge for movement about an axis extending substantially parallel to the walls of the trough; and means for moving the plate-like member about its axis of movement.
2. In stoker apparatus, the combination of a retort; means for feeding fuel longitudinally of the retort and upwardly toward the top thereof; a grate disposed along one side of the retort for receiving and supporting the fuel during combustion; and means disposed along the opposite side of the retort for pushing onto the grate the fuel overflowing from the retort, said last-mentioned means comprising a plate-like member pivoted to move about an axis extending substantially parallel to the retort.
3. In a furnace including a wall, the combination of a retort disposed along the furnace wall; means for feeding fuel longitudinally of the retort and upwardly toward the top thereof; a grate extending laterally from the side of the retort remote from the wall; and fuel pushing means disposed along the furnace wall for pushing onto the grate the fuel overflowing from the retort, said pushing means including a plate-like member pivotally supported at one end thereof, and means for moving said plate about its pivotal support.
5. 4. In combustion apparatus, the combination of a furnace including a side wall; a retort having spaced parallel side walls and one of the side walls being disposed along the furnace side wall; means for feeding fuel to said retort and upward toward the top thereof; a grate surface disposed laterally from the side wall of the retort remote from the furnace side wall; a sectional wall forming an upward extension of the retort side wall lying adjacent the furnace wall and piv-

totally supported at its lower end by such retort side wall; and means for moving the sectional wall about its pivotal support.

In testimony whereof, I have hereunto subscribed my name this 1st day of November, 1929.
